Patented Oct. 4, 1921.

UNITED STATES PATENT OFFICE.

EZEKIEL N. PARIS, OF SHAWNEE, OKLAHOMA.

CHURN.

1,392,789.

Specification of Letters Patent.

Patented Oct. 4, 1921.

Application filed November 15, 1920. Serial No. 424,149.

To all whom it may concern:

Be it known that I, EZEKIEL N. PARIS, a citizen of the United States, residing at Shawnee, in the county of Pottawatomie and State of Oklahoma, have invented certain new and useful Improvements in Churns, of which the following is a specification, reference being had therein to the accompanying drawings.

10 This invention relates to churns and has for an object to provide a churn having improved means for controlling the cream within the receptacle both as to its agitation and the controlling of the temperature of 15 such cream.

A further object of the invention is to provide a churn having reversely rotating dashers of the propeller type with an intermediate member for cutting the cream, performing a function not performed by the dashers as shown, or as ordinarily employed.

20 A further object of the invention is to provide beneath the receptacle a compartment employed for controlling the temperature 25 of the cream by the installation therein of a heating element if the temperature should be raised, or a cooling material if the temperature should be lowered.

With these and other objects in view the 30 invention comprises certain novel features, elements, units, parts, combinations and arrangements of parts as will be hereinafter more fully described and claimed.

In the drawings:

35 Figure 1 is a diametrical sectional view of the improved churn;

Fig. 2 is a transverse sectional view taken on line 2—2 of Fig. 1;

40 Fig. 3 is a detail sectional view taken on the mounting of one of the dashers, and

Fig. 4 is a detail perspective view of the cutting element.

Like characters of reference indicate corresponding parts throughout the several 45 views.

The improved churn which forms the subject matter of this invention comprises a receptacle, or container, 10, of any usual or ordinary shape, configuration, or size,— 50 here shown as cylindrical and with a vertical axis.

The container is provided with a bottom 11 and is supported in any approved manner, as by the feet 12. A cover member 13 is

55 provided, and while preferably this cover

member will be in sections, such sectional formation is not essential to the present invention. The cover member is provided with a screw cap 14, carrying a thermometer 15, by which the temperature of the 60 contents may be read from the exterior.

Within the receptacle 10 a hollow shaft 16 is mounted, extending upwardly through the cover member 13 and provided with a beveled pinion 17 intergeared by the beveled gear 18, actuated in any approved manner, as by the crank 19. At the lower end, the tubular shaft 16 is provided with a hub 20, secured thereto in any approved manner, as by the set screw 21, and such hub member is 70 provided with the dasher arms 22, which are reversely inclined, similar to the inclinations of a conventional propeller. At the lower end the tubular shaft 10 is provided with a bushing 23, through which extends the shaft 75 24. The shaft 24 is provided at its upper end with a beveled pinion 25, intergeared with a gear 18, and a bracket 26 is located upon the cover member 13, forming a bearing for the upper end of the shaft 24. The 80 bottom 11 is provided with a bearing 27 supporting the lower end of the shaft 24. It will be noted from Fig. 1 that the shafts 16 and 24 will be rotated in the opposite direction by the rotation of the gear 18. The 85 shaft 24 is provided with a hub 28 secured thereto in any approved manner, as by the set screw 29, and carrying dasher blades 30, which, like the dasher blades 22, are reversely inclined and their inclination such 90 as to move the contents in opposition to the movement provided by the blades 22. The action of the blades 30 is to move the contained cream upwardly, while the action of the blades 22 is to move it downwardly. 95 This forms an agitation between the blades, forming a zone of quiet. This zone of quiet is transected by a cutter 31, which is made substantially in the form of wire with coils 32, shown as three in number, but the invention is in no way limited to the number of coils so employed.

The cutter 31 is carried upon the hub 33, which is secured to the shaft 24 in any approved manner, as by the set screw 34. A 105 drain cock 35 communicates with the receptacle 10, from and through which the butter-milk may be discharged after the churning has been completed.

Beneath the bottom 11 is a receptacle 36, 110

which is adapted to support a medium for varying the temperature of the contained cream. As shown at Fig. 1, a lamp-like structure 37 is employed, but it is to be understood that this is not limited in any manner to such particular element, and any means for changing the temperature may be substituted therefor. It is not necessary that the element change the temperature by raising such temperature, and the lowering of such temperature by the employment of a cooling element is fully within the scope of the present invention.

It is believed that the operation and function of the several parts and their combinations will be fully understood from the foregoing.

What I claim to be new is:

In a churn having a vertical spindle, a blade structure comprising a socket adapted to be carried by said spindle and a rod one end of which rod is adapted to fit the socket with the rod extending radially from the spindle, means for retaining the rod immovably in the socket, the rod bent into a plurality of loops and affixed with the loops having their axes on chords of a circle having the axis of the spindle as their center.

In testimony whereof I hereunto affix my signature in presence of two witnesses.

EZEKIEL N. PARIS.

Witnesses:

L. L. HUMPHREYS,
M. M. MEEK.
